UNITED STATES PATENT OFFICE.

WILLIAM JORDAN PAUL, OF JERSEY CITY, NEW JERSEY, ASSIGNOR, TO PAUL, SIEWERS & MCKAY, OF NEW YORK, N. Y., A CORPORATION OF NEW YORK.

LOOSE-LEAF BINDER.

1,187,086.

Specification of Letters Patent. Patented June 13, 1916.

Application filed August 9, 1915. Serial No. 44,476.

To all whom it may concern:

Be it known that I, WILLIAM JORDAN PAUL, a citizen of the United States, residing in Jersey City, county of Hudson, State of New Jersey, have invented certain new and useful Improvements in Loose-Leaf Binders, of which the following is a specification.

My invention relates to binders for loose leaves and my particular improvements are applicable to binding loose leaves of any character of book, such for example as check and account books and my present improvements may be used with or without a book-cover and may be also used as an ordinary file for securing together papers in suitable bunches.

I have illustrated a type of my invention in the accompanying drawings, wherein; Figure 1, is a plan view of a loose-leaf binder in book form and containing my improvements with the lower left hand part of one cover being broken away. Fig. 2, is an enlarged vertical section taken longitudinally of the book, the plane of the section being indicated by the lines 2-2, Fig. 1. Fig. 3, is an enlarged top plan view of the binding parts, shown as detached from the book back and is partly in horizontal section and partly broken away. Fig. 4, is an enlarged vertical sectional view of the binding parts, detached, and broken away near the right hand end. Figs. 5, and 6 are detailed views of the locking bolt and its actuating cam, showing the relative positions of the parts in locked and unlocked positions, respectively, with the bolt and the detachable member which carries it, being broken away at each side of the cam. These two views being on a larger scale than the other views.

Referring to the drawings, in which like numbers of reference designate like parts throughout, 1 indicates a base plate or member on which fixed upright impaling posts 2, are mounted a suitable distance apart and as many in number as desired, though for an ordinary size of binder it will suffice to have two posts as herein shown. These posts have the loose leaves 3, impaled or strung upon them, the leaves usually having suitable perforations 4, through which the posts pass loosely, the perforations being placed so as to register with the posts.

The detachable member which is releas-

ably locked to the free ends of the impaling posts, comprises a flat tube 5, having circular holes 6, formed through its inner side for receiving the reduced ends 7, of the posts, which ends fit into said holes so that the annular shoulders 8, take against the outer side of the tube and act to space the detachable member from the base-member carrying the posts.

Near its free end each post is formed with a peripheral groove 9, with which the narrow part of the locking slots 10 of the bolt 11, engage. The bolt 11, is a flat bar mounted within the flat tube and is provided with raised places 12, formed by making transverse bends in the bar near each end thereof. These raised places bear against the inner walls of the tube and make sufficient friction between the parts to prevent the bolt being too loose in the casing in which it slides. At the center of length, the bolt is raised slightly at 13, (see Fig. 4) where it is formed with an L-shaped or right-angled slot 14, in which works the cam-pin 15, depending from the underside of the disk-shaped head 16, of the cam. The stud 17 fixed to the center of the head, passes loosely through the slot and into the side of the flat tube 5 where it is mounted to turn so that the cam can be rocked back and forth on the axis of the stud. The stud is mounted to turn by reducing its outer end where it passes through the wall of the tube and then making the extreme end flat, as shown in Fig. 4.

The outer face of the cam head 16, is provided with a slot 18, adapted to readily receive a blade or tool by means of which the cam is turned about a quarter of a circle.

When the bolt is shot, the cam-pin 15, stands in the angle of the L-shaped slot, as shown in Fig. 5. By turning the head 16 of the cam a quarter of a circle in the direction opposite to that in which the hands of a clock move, the cam pin 15 is caused to travel along the transverse branch of the slot toward the side edge of the bolt and on an arc the center of which is coincident with the axis of the stud 17. This causes the cam-pin to bear against one side of the slot and thereby push the bolt in the direction in which the pin travels and a sufficient distance to release the bolt from the post heads, the latter position of the bolt being shown in Fig. 6. In order to shoot the bolt and

lock the pins, the cam head 16, is turned a quarter of a circle from the position shown in Fig. 6 and in the reverse direction from that just described. This causes the cam 5 pin to retrace its path of travel and to bear against the opposite edge of the slot and thereby force the bolt in the reverse direction.

The locking slots 10, of the bolt have their 10 corresponding ends enlarged at 20, to permit the heads of the posts to pass freely in and out of the slots in putting the binder together and taking it apart. When the bolt is slid so as to bring the narrow part of the 15 slots in the grooves in the post heads, the parts are then locked securely together.

In the book herein shown the base member 1, is incorporated in the book back 21, likewise the detachable member the two 20 parts lying opposite to each other as shown in Fig. 2. The book covers 22 and 23, inclose the loose leaves 3, so as to make a complete and substantial book.

It will be noted that the detachable member 25 carrying the bolt is comparatively thin in cross section and that the disk-shaped head of the cam which is set in the side of said member is flat and substantially flush with the surface of the member, thus avoiding any objectionable projecting part. The 30 binder parts may all be made of metal and when assembled present a very compact and durable structure.

It will also be noted that the bolt and its 35 actuating cam are completely housed within the flat tube 5, and this is an important advantage in devices of this character.

In operating the device, the detachable member is first released from the impaling 40 posts by turning the cam, as described, and then this member is lifted from the posts upon which the loose perforated leaves may then be placed. Thereupon the detachable member is placed back upon the free ends of 45 the posts and the cam turned so as to move the bolt into locking position with the posts. The parts are thus firmly held together with the leaves in place. When the leaves are to be removed, the detachable member is un- 50 locked from the posts and removed so as to permit the leaves to be lifted off the posts.

I wish to be understood as not limiting my invention to the particular form herein shown, as it is evident that changes may be 55 made in the various parts thereof, without however departing from the spirit of my invention.

Having thus described my invention, what I claim and desire to secure by Letters Patent is:

1. In a loose leaf binder, the combination of a base-member provided with suitably spaced impaling-posts, a detachable flat tube provided with lateral openings spaced 60 to register with the ends of said impaling-

posts, an endwise sliding bolt within said tube and formed with openings for engaging and locking the inserted ends of said impaling-posts, said bolt being provided with an operating slot having a bend therein, a 70 bolt operating cam comprising a disk provided on its underside with a central stem mounted in the interior wall of said tube so as to turn and an eccentric pin fixed on the underside of said disk and loosely engaging 75 the said slot in the bolt, the said tube being provided with an orifice in which said disk loosely fits and by which it is exposed upon the exterior of said tube, the said stem of the cam passing loosely through the said slot in 80 the bolt, substantially as described.

2. In a device of the class described, the combination of a base-member provided with suitably spaced impaling posts, a detachable member comprising a tube 85 provided with lateral openings spaced to register with said posts and adapted to receive the ends thereof, an endwise sliding bolt mounted within the tubular member and adapted to engage the inserted ends of said 90 posts and to lock them to said detachable member and provided with raised places for increasing the friction between the bolt and the interior of the tubular member, and a cam mounted on said detachable member 95 and operatively connected with said bolt for shooting and retracting it.

3. In a loose-leaf binder, the combination of a base-member provided with suitably spaced impaling-posts, a detachable flat tube 100 provided with lateral openings spaced to register with the ends of said impaling-posts, an endwise sliding bolt within said tube and formed with openings for engaging and locking the inserted ends of said impaling-posts, said bolt being provided with an operating slot having a bend therein, a bolt operating cam comprising a circular disk provided on its under side with a central stem mounted in the interior wall of 110 said tube so as to turn and an eccentric pin fixed on the underside of said disk and loosely engaging the said slot in the bolt, the said tube being provided with a circular orifice in which said disk loosely fits and by 115 which it is exposed upon the exterior of said tube, and being substantially flush therewith, the outer face of said disk being formed with a slot for receiving an instrument to turn the disk, said stem of the cam 120 passing loosely through the said slot in the bolt, substantially as described.

4. In a loose leaf binder, the combination of a base-member provided with suitably spaced impaling-posts, a detachable flat tube 125 provided with lateral openings spaced to register with the ends of said impaling-posts, an endwise sliding bolt within said tube and formed with openings for engaging and locking the inserted ends of said im- 130

paling-posts, the said bolt having an upwardly extending bent part provided with an operating-slot, a bolt-operating cam comprising a disk provided on its underside with a central stem projecting downwardly through said bolt-operating slot and having its lower end mounted in the interior wall of said tube so as to turn, an eccentric pin fixed in the underside of said disk and projecting loosely into the bolt-operating slot so that its lower end clears the interior wall

5 of the tube, and the said tube being provided with a lateral orifice in which said disk loosely fits, substantially as described.

In testimony whereof, I have hereunto 15 set my hand in the presence of the two subscribing witnesses.

WILLIAM JORDAN PAUL.
